FILLING DEVICE

Nathan Zepelovitch, New York, N. Y., assignor to
Nahum A. Bernstein, New York, N. Y.

Application April 28, 1950, Serial No. 158,643

8 Claims. (Cl. 226—63)

1

This invention relates to filling devices and particularly to an automatic externally disposed filling device for fluid type writing instruments.

Conventional fountain pens of the split nib or stylographic types are normally filled through the action of an internally disposed filling mechanism, creating successive pressure variations within the ink reservoir through the manual actuation of a plunger or lever. The conventional filling mechanisms utilizing either a plunger or lever, in addition to limiting the space available for an ink reservoir within the barrel of the pen, are, due to lack of space, normally relatively delicately constructed. The delicate construction usually results in an increase in production costs and ultimate cost of the pen and also often-times results in a shortened life of the writing instrument due to breakage or other defection of the relatively delicate filling mechanism.

The conventional filling mechanisms, utilizing pressure variations within the ink reservoir, normally do not assure an effective flushing of both the ink and air channels of the pen during filling operations. If the air channel is clogged or plugged, the pen may be filled without a cleansing or flushing of this channel, and the pen, although having its ink reservoir relatively full of ink, will write poorly due to an uneven flow of ink from the reservoir to the writing nib or tip.

In addition, filling the conventional type pens is normally an inconvenient and relatively sloppy procedure requiring a careful insertion, depth-wise, of the pen into the container and a maintenance of position during filling operations. Certain common expedients, such as tiltable bottles and bottles having internally disposed wells are conventionally utilized to overcome this defect and to maintain a required predetermined ink level for filling purposes. In any event, a filling of the conventional type pen must usually be accompanied by a subsequent cleansing of the portion of the pen barrel adjacent the writing tip.

This invention may be briefly described as a fluid writing instrument filling device disposed externally of and separate from the writing instrument and adapted to be removably mounted on a writing fluid container or bottle for providing a simple, rapid, clean and efficient filling and cleansing of fountain pens. The device includes a plurality of interconnected complementary chambers which are deformable in response to manual depression of a writing instrument placed in operative relationship therewith for removing any residue of ink contained

2

within the ink reservoir and for flushing and cleansing both the air and ink channels of the writing instrument, and are further deformable in response to a release of the manual depression of the writing instrument for automatically filling the previously emptied ink reservoir independent of the level of ink in the supply container and for further flushing the air and ink passages of the writing instrument as the ink reservoir is being refilled with fluid ink.

An object of this invention is to provide an automatic filling device for fluid type writing instruments.

Another object of this invention is to provide a fluid writing instrument filling device disposed externally of and separate from the writing instrument.

Another object of this invention is to provide an automatic filling device for writing instruments that is simple in construction and further provides a rapid filling of fluid type writing instruments.

Another object of this invention is to provide an automatic filling device for writing instruments which cleanses and flushes the ink and air channels of a writing instrument during filling operations.

Another object of this invention is to provide an automatic filling device for fluid type writing instruments which permits the use of a fountain pen having a greatly enlarged capacity for ink storage.

Another object of this invention is to provide an automatic filling device for writing instruments which permits a writing instrument to be filled in a rapid, clean and simple manner.

Another object of this invention is to provide an automatic filling device for writing instruments that is simple and inexpensive in construction.

A further object of this invention is to provide an automatic filling device for writing instruments that is massive, strong and of enduring characteristics.

45 Other objects and advantages of the invention will be pointed out in the following disclosure and claims and illustrated in the accompanying drawings which describe, by way of example, the principle of the invention and the presently preferred embodiment of the filling mechanism applying this principle.

Referring to the drawings:

Fig. 1 is a cross sectional view of the filling mechanism positioned in operative relationship with an ink bottle;

Fig. 2 is an enlarged sectional view illustrating the positioning of a fountain pen in operative relationship with the filling device;

Fig. 3 is a cross sectional view showing the relationship between the various elements of the filling mechanism during the first stage of the filling operation; and

Fig. 4 is a cross sectional view showing the relationship between the various elements of the filling mechanism during the second stage of the filling operation, and illustrating a modified embodiment of the invention.

Referring to Figs. 1 and 2, the filling device is there illustrated positioned in static operative relationship with an ink container.

There is provided an outer cover member 10 having a centrally disposed bore 12. The cover member 10 is adapted to be threadedly engaged with the mouth of an ink supply container 14, as at 16. A resilient deformable washer 18, positioned between the lip of the ink supply container 14 and the abutting surface of the cover member 10, provides a hermetic closure for the ink supply container 14.

The cover member 10 may be shaped and colored to provide a pleasing, decorative effect and is easily molded from suitable plastic materials. The underside of the cover member 10 is provided with a cylindrically shaped recess 20. Threadedly engaged with the underside of the cover member 10 on the bounds of the recess 20 is an annular bowl 22 having a centrally disposed aperture 24 sized equivalently with and positioned beneath the bore 12 of the cover member 10. The bowl 22 cooperates with the recess 20 to provide a cylindrically shaped compartment generally designated as 26.

Positioned within the bore 12 in the cover member 10 and the aperture 24 in the bowl 22 is a vertically displaceable cylindrical sleeve 28. The compartment 26 formed by the recess 20 in the cover 10 and the bowl 22 is divided into complementary upper and lower chambers 34 and 36, respectively, by a horizontally disposed annular deformable membrane 38 hermetically secured at its periphery in the joint between the bowl 22 and the cover member 10. The membrane 38 is hermetically secured to the vertically displaceable sleeve 28 positioned within the bore 12 and the aperture 24 and is encompassed over a major portion of its radius by the substantially horizontally disposed rigid undeformable discs 40 and 42 mounted on the outer peripheral surface of the sleeve 28 and extending radially outward therefrom. The discs 40 and 42 do not extend to the bounds of the compartment 26 and serve to provide a rigid mounting for the portions of the deformable membrane 38 positioned therebetween.

The vertically displaceable sleeve 28 is closed at its lower end by an annular closure plate 46 which may, if desired, be integral with the sleeve 28. Permanently mounted in the annular opening of the closure plate 46 and extending inwardly into the interior of the vertically disposed sleeve 28 is a substantially vertically disposed rigid tube 48. The tube 48, being permanently secured to the vertically displaceable sleeve 28 moves vertically in conjunction therewith when said sleeve 28 is vertically displaced.

Mounted on the upper end of the vertically displaceable sleeve 28 and positioned substantially flush with the upper surface of the cover member 10 is a horizontally disposed elastic seating washer 50. The washer 50 is annular in

shape and provided with a conically shaped centrally disposed opening 52, said opening being wider at its upper extremity in the line of the upper surface of the cover member 10 and narrower at its lower extremity. The washer 50 is adapted to hermetically seat the lower portion of the barrel of a writing instrument in a manner which will be described in detail at a later point in this specification.

10 The portion of the substantially vertically disposed rigid tube 48 positioned within the vertical sleeve 28 is externally encompassed by a vertically disposed elastic tube 58. The elastic tube 58 rests upon the annular closure plate 46, closing the bottom of the sleeve 28, and extends upwardly and abuts, in static relationship, the underside of the seating washer 50. The elastic tube 58 is closed adjacent its upper extremity by a conically shaped elastic deformable ring 60 having a small central opening 62 coaxially disposed with respect to the axes of the rigid tube 48 and the vertically displaceable sleeve 28.

The vertically displaceable sleeve 28 is thus movable within the bore 12 of the cover member 10 and aperture 24 of the annular bowl 22. To provide a secure hermetic joint between the vertically displaceable sleeve 28 and the annular bowl 22, an elastic deformable washer 70 is secured to the surface of the bowl 22 and encompasses the sleeve 28. The elastic washer 70 functions as a pressure-tight gasket when the vertically displaceable sleeve 28 is moved with respect to the bowl 22. A similar elastic washer 72 is secured to the underside of the recess 20 in the outer cover 10 and encompasses the vertically displaceable sleeve 28. The washer 72 also functions as a pressure-tight gasket when the vertically displaceable sleeve 28 is moved with respect to the cover member 10. The washers 70 and 72 may be hermetically secured to the sleeve 28 to assure the maintenance of the pressure-tight relationship.

15 The lower extremity of the vertically disposed rigid tube 48 permanently mounted in the closure plate 46 extends downwardly into the ink supply container 14. The lower extremity of the tube 48 is slidably positioned concentrically within the auxiliary tube 76, a suitable elastic washer 78 being positioned intermediate said tubes 48 and 76 to provide a secure hermetic seal therebetween. The tube 76 is adapted to rest on the bottom of the ink supply container 14 and is provided with a plurality of internally disposed shoulders for internally supporting a biasing spring 80 to bias the rigid tube 48 and the vertically displaceable sleeve 28 permanently secured thereto in an upwardly disposed position. The lower extremity of the auxiliary tube 76 is adapted to rest on the bottom of the ink supply container 14 and is provided with a plurality of small apertures 84 to permit a flow of ink from the main supply within the container 14 into the tubes 76 and 48.

20 The deformable membrane 38 positioned between the discs 40 and 42 mounted on and extending radially outwardly from the vertically displaceable sleeve 28 divides the compartment 26 into the complementary upper and lower annular shaped chambers 34 and 36, respectively. The upper chamber 34 is connected to the interior of the hermetically sealed ink supply container 14 by a suitable small channel 96 positioned within the vertically displaceable sleeve 28. The lower chamber 36 is connected to the annular space positioned intermediate the vertically displaceable sleeve 28 and the elastic tube 58 con-

tained therein by a suitable small channel 92 in the side of the vertically displaceable sleeve member 28.

In the above portions of this specification the structure of the filling device in a static state hermetically positioned in the mouth of the ink supply container 14 has been described. In this condition, leakage of ink from the ink supply container 14 through the filling device is prevented irrespective of whether the container is tilted or turned completely over, as the only possible leakage opening, i. e. the centrally disposed opening 62 in the elastic ring 60, is maintained closed due to the elastic properties of the ring 60.

Fig. 2 illustrates the positioning of a writing instrument in operative relationship with the filling device described above. As the writing point 100 of the writing instrument 102 is inserted into the opening 62 in the elastic seating washer 50, the action of opening the filling device begins. A further insertion of the writing tip 100 into the opening 62 results in an engagement of the elastic ring 60 by the tip 100. The pressure of the writing tip 100 entering the elastic ring 60 depresses the elastic tube 58 causing said tube to withdraw downwardly from its static position abutting the elastic seating washer 50. The downward movement of the elastic tube 58 continues in response to continued depression of the writing instrument 102 until the underside of the elastic ring 60 engages the upper portion of the rigid tube 48. This arrests the deformation of the elastic tube 58 and a further downward pressure of the writing tip 100 forces said writing tip into the opening 62. The ring 60 due to its elastic characteristics firmly encompasses the writing tip 100 and hermetically seals said tip within the ink supply tube 49 which extends into the container 14. At the same time, the elastic seating washer 50, due to its elastic characteristics, closes hermetically about the bore 104 of the writing instrument 102. The writing instrument is now positioned for the filling and cleansing operations.

It will be noted that when the writing instrument is placed in operative relationship with the filling device as illustrated in Fig. 2, the writing tip 100, which is in fluid connection with the ink reservoir 108 within the body of the writing instrument through the channel 110, is directly connected to the ink supply within the ink supply container 14 through the ink supply tubes 48 and 76. In addition, the lower chamber 38 is connected via the channel 92 to the space disposed between the elastic tube 58 and the sleeve 28 which in turn is connected to an air channel 166 venting the ink reservoir of the fountain pen. Thus, both the ink supply channel 110 and the air vent channel 166 of the writing instrument 102 are both individually and directly connected to the various chambers especially provided in the filling device which are hermetically sealed from one another and from the external atmosphere.

Fig. 4 illustrates a slightly modified embodiment of the invention. There is provided an outer cover 118 enclosing an annular compartment 120 and having a centrally disposed bore 122. The cover member 118 is adapted to be threadedly engaged with the conventional raised glass threads 124 on the exterior surface on the mouth of an ink supply container 126. A resilient deformable washer 128 positioned between the lip of the mouth of the ink supply

container 126 and the abutting surface of the cover member 118 provides a hermetic closure for said container.

Positioned within the bore 122 of the cover member 118 is a vertically displaceable sleeve 130. The compartment 120 is divided into complementary upper and lower chambers 132 and 134, respectively, by a horizontally disposed annular deformable membrane 136 hermetically secured at its periphery to the side walls of the cover member 118 and provided with an annular centrally disposed opening hermetically secured to the vertically displaceable sleeve 130. The membrane 136 is encompassed over a major portion of its radius by substantially horizontally disposed rigid discs 138 and 140 mounted on the outer peripheral surface of the sleeve 130 and extending radially outward therefrom. The discs 138 and 140 do not extend to the bounds of the compartment 120 and serve to provide a rigid mounting for the portions of the deformable membrane 136 positioned therebetween.

Centrally disposed within the vertically displaceable sleeve 130 and extending downwardly therefrom is a tube 142. The lower portions of the tube 142 are concentrically and slidably contained within an auxiliary tube 144 provided with suitable apertures 146 at the portion thereof resting on the base of the ink supply container 126. A suitable gasket or washer 148 is positioned between the tubes 142 and 144 to maintain said tubes in hermetic relationship during movement of said tube 142 with respect to said tube 144. A spring 150 encompassing the tube 142 rests upon the upper extremity of the tube 144 and biases the sleeve 130 in an upwardly disposed position.

The upper portion of the sleeve 130 is provided with an annular closure plate 152 which supports an elastic washer 154 encircling the annular opening therein. The tube 142 at its upper extremity is encompassed by an annular deformable washer 156 having an opening axially disposed with respect to the bore of the tube 142. The washer 156 is adapted to hermetically position the writing tip of a writing instrument placed in operative relationship with the filling device. In a similar manner the elastic washer 154 positioned encircling the opening in the closure plate 152 is adapted to hermetically position the bore of a writing instrument 102 placed in operative relationship therewith.

The vertically displaceable sleeve 130 is thus movable with the centrally disposed bore 122 of the cover member 118. To provide a secure hermetic joint between the vertically displaceable sleeve 130 and the portions of the centrally disposed bore 122 adjacent thereto, an elastic deformable washer 168 is secured to the underside of the upper surface of the cover member 118 and hermetically encompasses the sleeve 130. A similar elastic washer 170 is secured to the bottom wall of the compartment 120 and hermetically encompasses the adjacent portion of the displaceable sleeve 130.

The membrane 136 positioned between the discs 138 and 140 divides the compartment 120 into the upper and lower chambers 132 and 134, respectively. The upper chamber 132 is connected to the interior of the hermetically sealed ink supply container 126 by a suitable small channel 172 disposed within the sides of the sleeve 130. The lower chamber 134 is connected 75 with the interior portions of the sleeve 130 inter-

mediate the washers 154 and 156 by a suitable channel 174 piercing the side of the sleeve 130.

The embodiment set forth in Fig. 4 illustrates a construction positioning the upper and lower chambers 132 and 134 externally of the ink supply container 126 and is of slightly different shape than the embodiment of the invention illustrated in Figs. 1 through 3 and described above in the earlier portions of this specification. However, this embodiment functions in an exactly similar manner to the embodiment set forth in Figs. 1 through 3.

Reference will be had to Fig. 3 for an explanation of the mode of operation of the filling device. It should be noted at this time that the explanation of operation is specific to the embodiment set forth in Fig. 3, but it should be clearly understood that the slightly modified embodiment illustrated in Fig. 4 functions in a similar manner.

After the writing instrument has been placed in operative relationship with the filling device, as illustrated in Fig. 2 and as explained at an earlier portion of this specification, the opening of the ink supply container 14 has been completed. Referring now particularly to Fig. 3, further downward pressure of the writing instrument 102 initiates the action of emptying any ink contained within the ink supply reservoir of the fountain pen and initiates a cleansing and flushing of the ink supply channel 110 and the air vent channel 106 extending upwardly to the top of the ink reservoir 108.

After the pen has been placed in operative relationship with the filling device as illustrated in Fig. 2, the elastic tube 58 can no longer be further depressed and the elastic ring 62 cannot be further widened. A further manual downward displacement of the writing instrument 102 results in a downward displacement of the displaceable sleeve 28. The downward displacement of the sleeve 28 moves the rigid tube 48 connected thereto downwardly within the tube 76 resting upon the bottom of the ink supply container 14. The downward movement of the sleeve 28 and the tube 48 is opposed by the biasing spring 80 positioned within said tube 76.

The downward movement of the sleeve 28 results in a downward movement of the membrane 38 positioned between the discs 40 and 42. The deformation and downward movement of the membrane 38 results in the lower chamber 36 being decreased in size with an accompanying increase in the air pressure therein. The decrease in volume of the lower chamber 36 is also accompanied by a complementary increase in the volume of, and accompanying decrease in pressure in the upper chamber 34. As the upper chamber 34 increases in volume and the pressure decreases therein, there occurs a simultaneous decrease in pressure within the hermetically sealed ink supply container 14, said chamber 34 and container 14 being connected by the channel 90.

The decrease in volume of and increase in pressure within the lower chamber 36 obtained through the downward displacement of the sleeve 28 results in a simultaneous increase in pressure in the space contained between the elastic tube 58 and the sleeve 28 via the channel 92. As this space is directly connected with the air vent channel 106 of the writing instrument 102, the pressure within the ink reservoir 108 is also increased. The overpressure created within the ink reservoir of the fountain pen, together with

the complementary decrease in pressure within the container 14 causes the remnants of ink contained therein to flow downwardly via the channel 110 through the writing tip 100 into the container 14.

Thus depression of the vertically displaceable sleeve 28 results in a decrease in pressure within the ink container 14 and a concomitant and complementary increase in pressure within the fountain pen 102 which effectively empties the ink reservoir 108. During this portion of the filling cycle the channel 106 is cleansed by a flow of air into the reservoir 108 and the channel 110 in the writing instrument 102 is cleansed by a flow of ink from the reservoir 108.

When the downward movement of the vertically displaceable sleeve 28 is halted by the engagement of the washer 70 by the disc 42, the action of emptying the ink reservoir 108, together with the first cleansing of the air and ink channels of the fountain pen is halted.

If manual downward pressure on the writing instrument 102 is then released, the spring 80, which has been previously compressed during the downward movement of the sleeve 28, moves the tube 48 and the sleeve 28 connected thereto upwardly. The upward movement of the vertically displaceable sleeve 28 in response to the action of the spring 80 results in an accompanying upward movement of the membrane 38 and the discs 40 and 42. The upward movement of the membrane 38 and the discs 40 and 42 results in an increase in volume of and decrease in pressure within the lower chamber 36. This decrease in pressure is transmitted through the channel 92 to the space positioned between the elastic tube 58 and the vertically displaceable sleeve 28 and further transmitted through the air vent channel 106 of the writing instrument 102 to the ink reservoir 108.

As the lower chamber 36 is being increased in volume by the upward displacement of the sleeve 28, the complementary upper chamber 34 is being decreased in volume with an accompanying increase in pressure therein. The pressure increase in the upper chamber 34 is transmitted through the channel 90 to the ink supply container 14.

The complementary pressure unbalance created by the upward movement of the vertically displaceable sleeve 28, i. e. the pressure decrease within the ink reservoir 108 of the writing instrument 102 and the pressure increase within the ink container 14, results in a forcing of ink through the openings 80 in the tube 76 and upwardly through said tube 76 and tube 48 into the ink reservoir 108 of the writing instrument 102 via the ink channel 110.

It should be noted at this time that the filling action described above results in a second cleansing of the air vent channel 106 and the ink channel 110 of the writing instrument 102.

After the vertically displaceable sleeve 28 is limited in its upward movement by having the disc 40 abut the washer 72, the cleansing and filling action is completed. A slight pull on the barrel of the writing instrument 102 causes the writing tip 100 to be easily withdrawn from the opening 62 in the elastic ring 60 and the cone 104 to be easily withdrawn from the elastic sealing washer 50.

As the pen 102 is withdrawn from operative relationship with the filling device, the elastic tube 58 moves upwardly, the elastic ring 60 contracts and the opening 62 is closed. The upward move-

ment of the elastic tube 58 continues until said tube abuts the sealing washer 50. At this point the device is again in its static position as illustrated in Fig. 1.

Having thus described my invention, I claim:

1. A device for filling writing instruments adapted for cooperation therewith and for attachment to an ink supply container, said device comprising, a cover member, a displaceable writing instrument seating member mounted in said cover member, a tube dependent from said seating member and shaped to hermetically connect the ink within an ink supply container with the writing tip of a writing instrument seated in said seating member, a chamber formed by and disposed within said cover member connected to the ink supply container by passage means in said seating member, a second chamber formed by and disposed with said cover member connected to the ink reservoir of the writing instrument seated on said seating member by second passage means in said seating member, a deformable membrane hermetically secured to said displaceable seating member and forming a common wall for and between said chambers, displacement of said seating member being effective to flex said deformable membrane and vary the volume of said chambers, for creating pressure unbalances within the writing instrument seated on said seating member and within the ink supply container to empty and fill said writing instrument.

2. A device for filling writing instruments adapted for cooperation therewith and for attachment to an ink supply container, said device comprising, a cover member, a displaceable writing instrument seating member mounted in said cover member, a tube mounted in said seating member and dependent therefrom shaped to hermetically connect the ink within an ink supply container with the writing tip of a writing instrument seated in said seating member, a chamber formed by and disposed within said cover member, an opening in said seating member connecting said chamber with the ink supply container, a second chamber formed by and disposed with said cover member, an opening in said seating member connecting said chamber with the ink reservoir of the writing instrument seated on said seating member, a deformable membrane hermetically secured to said displaceable seating member and forming a common wall for said chambers, the volume of said first and second chambers being variable in response to flexure of said deformable membrane resulting from displacement of said seating member in one direction for increasing the pressure within the writing instrument seated in said seating member and decreasing the pressure within the ink supply container to empty said writing instrument, and for decreasing the pressure within said writing instrument and increasing the pressure within said ink supply container to fill said writing instrument in response to displacement of said seating member in a second direction.

3. A device for filling writing instruments adapted for cooperation therewith and for attachment to an ink supply container, said device comprising, a cover member for hermetically sealing the ink supply container, a displaceable writing instrument seating member mounted in said cover member, a tube mounted in said seating member and dependent therefrom into said ink supply, deformable means mounted on said tube shaped to hermetically engage the writing tip of a writing instrument seated in said seat-

ing member, a chamber formed by and contained within said cover member, passage means in said seating member connecting said chamber to the ink supply container, a second chamber formed by and contained within said cover member, second passage means in said seating member connecting said second chamber to the ink reservoir of a writing instrument seated on said seating member, a deformable membrane hermetically secured to said displaceable seating member and to the cover member forming a common intermediate wall for said chambers, the volume of said first and second chambers being variable in response to flexure of said deformable membrane resulting from displacement of said seating member for creating complementary pressure unbalances within said writing instrument seated on said seating member and within the ink supply container to empty and fill said writing instrument.

4. A device for filling writing instruments adapted for cooperation therewith and for attachment to an ink supply container, said device comprising, a cover member for hermetically sealing an ink supply container and having a centrally disposed bore, a vertically displaceable sleeve mounted within said bore, a writing instrument seating element mounted on said sleeve, an ink supply tube concentrically contained within said sleeve and dependent downwardly therefrom into the ink supply container, a writing tip seating element mounted on said ink supply tube for hermetically connecting the writing tip of a writing instrument seated in said writing instrument seating element with the ink supply, a spring for upwardly biasing said displaceable sleeve, a chamber formed by and contained within said cover member, an opening in said sleeve connecting said chamber with the ink supply container, a second chamber formed by and contained within said cover member, a second opening in said sleeve connecting said second chamber to the ink reservoir of a writing instrument seated on the writing instrument seating element, a deformable membrane hermetically secured to said displaceable sleeve and to said cover member forming a common deformable wall intermediate said chambers, the volume of said first and second chambers being variable in response to downward displacement of said sleeve for increasing the pressure within the ink reservoir of the writing instrument and simultaneously decreasing the pressure within the ink supply container to empty said writing instrument, and for decreasing the pressure within said ink reservoir and increasing the pressure within said ink supply container to fill said writing instrument in response to the upward displacement of said sleeve under the influence of said spring.

5. A device for filling writing instruments of the type having an ink reservoir, a writing tip in fluid communication therewith and an air passage venting said ink reservoir, and adapted for cooperation therewith and for hermetic attachment to an ink supply container, said device comprising a cover member for hermetically sealing the ink supply container, a displaceable writing instrument seating member mounted in said cover member, a tube mounted in said seating member and dependent therefrom into said ink supply container, shaped means mounted upon the portion of said tube disposed within said seating member to hermetically connect a writing tip with the fluid ink in the supply container, said cover member shaped to provide an internal chamber disposed around said seating member,

a deformable membrane secured to said displaceable seating member and disposed within said chamber, said deformable membrane dividing said internally disposed chamber into a pair of complementary chambers having a common wall, an opening in said seating member connecting one of said chambers to the air passage in said writing instrument to vary the pressure within said ink reservoir in response to the displacement of said seating member, and a second opening in said seating member connecting the second of said chambers with said ink supply container to vary the pressure therein in response to the displacement of said seating member.

6. A method of filling writing instruments of the reservoir type comprising the steps of placing the writing instrument and the reservoir thereof in hermetic closed circuit relationship with the ink in an ink supply container, creating a pressure increase within said reservoir simultaneously with a pressure decrease within said ink container, and a subsequent pressure increase within said container simultaneously with a pressure decrease within said reservoir.

7. A device for filling writing instruments adapted for cooperation therewith and for attachment to an ink supply container, said device comprising a cover member, a displaceable writing instrument seating member mounted in said cover member, a tube dependent from said seating member for hermetically connecting the ink within the ink supply container with the writing tip of a writing instrument when said instrument is seated in said seating member, said cover member shaped to provide a pair of internally disposed chambers having a common deformable wall, passage means connecting one of said chambers with said ink supply container and the other of said chambers with said writing instrument, the volume of said chambers being variable in response to displacement of the seating member for creating complemental pressure unbalances

within the writing instrument and ink supply container to empty and fill the writing instrument.

8. A device for filling writing instruments adapted for cooperation therewith and for attachment to an ink supply container, said device comprising a cover member, a displaceable writing instrument seating member mounted in said cover member, a writing tip receiving tube mounted within said seating member and dependent therefrom into said ink supply, said cover member shaped to provide an internal chamber disposed around said seating member, a deformable wall member disposed within said internal chamber and secured to said displaceable seating member, said wall member dividing said internal chamber into a pair of complementary chambers having said wall member as a common wall therebetween, and passage means transmitting fluid pressure in response to displacement of said seating member and said wall member disposed within said seating member connecting one of said pair of complementary chambers with said writing instrument and the other of said pair of chambers with said ink supply container for increasing the pressure within the writing instrument and decreasing the pressure within the ink supply container during emptying operations and for decreasing the pressure within the writing instrument and increasing the pressure within the ink supply chamber during filling operations.
